Primary Examiner — Adir Aronovich*Assistant Examiner* — Ramzi Almatrahi(74) *Attorney, Agent, or Firm* — Patents on Demands P.A.; Brian K. Buchheit; Scott M. Garrett(57) **CLAIM**

The ornamental design for a panoramic optical device, substantially as shown and described.

DESCRIPTION

FIG. 1 is a perspective view of a panoramic optical device in accordance with the present design.

FIG. 2 is a side elevation view thereof.

FIG. 3 is a side elevation view rotated 180 degrees from the view shown in FIG. 2.

FIG. 4 is a side elevation view rotated 90 degrees from the view shown in FIG. 2.

FIG. 5 is a side elevation view rotated 270 degrees from the view shown in FIG. 2.

FIG. 6 is a top plan view thereof; and,

FIG. 7 is a bottom plan view thereof.

The broken lines depict portions of a panoramic optical device in which the design is embodied and form no part of the claimed design.
